UNITED STATES PATENT OFFICE.

AUGUST DANIELSON, OF EVERETT, WASHINGTON.

LOADING ATTACHMENT FOR CABLEWAYS.

1,285,565.

Specification of Letters Patent. Patented Nov. 19, 1918.

Application filed April 28, 1917. Serial No. 165,064.

To all whom it may concern:

Be it known that I, AUGUST DANIELSON, a citizen of the United States, residing at Everett, in the county of Snohomish and 5 State of Washington, have invented a new and useful Improvement in Loading Attachments for Cableways, of which the following is a specification.

This invention relates to cableways, particularly to such as are used for logging, 10 although the invention may be applied to the handling of other objects than logs. The invention consists of a device to be used in connection with cableways designed to facilitate the loading of the logs upon cars. 15 It is, therefore, called a loading attachment for cableways.

The object of this invention is to provide a mechanism which may be employed in 20 connection with logging cableways, whereby the transfer of logs from the cableway to the car may be secured more expeditiously and conveniently.

The invention comprises the parts and 25 combinations of parts which will be herein-after described and then particularly pointed out in the claims concluding the description. The accompanying drawings show the device applied in the preferred manner.

30 Figure 1 is an elevation showing the head mast and the delivering and loading end of a logging cableway having the invention applied thereto.

Fig. 2 is a plan view of the same.

35 It is the custom in operating cableways for logging, to establish a head mast or tree from which the cableway extends and about which the cableway is moved as the logging progresses. In consequence, the 40 operation of the cableway for any one setting covers a segment of a circle having its center at the head tree. Its outer end is moved in succession from one segment to the next, as the logging progresses.

45 The railroad, over which the logs are to be conveyed is intended to run alongside the head tree. The present invention is designed to facilitate the loading of the logs upon the cars and to overcome the difficulties which 50 would otherwise accompany this work due to the changing position of the cableway.

The main cableway is indicated at 2. Upon this is placed a carriage 20, which travels back and forth with the logs. The 55 fall-line rope, or the line which is used to attach to the logs in bringing them in, is

represented at 21. This cableway is supported in elevated position from a head tree or mast 1. This cableway, and the means for operating it, are, or may be, of any suitable 60 construction. As my invention does not reside in this part of the apparatus, I have not illustrated the same in detail and will not attempt further description thereof.

In conjunction with the main cableway, a 65 loading cableway is employed. This loading cableway employs a trackway cable 3 which extends from an elevated support on the head mast and thence to an anchorage, as 31, located at some distance from the head mast 70 and fairly close to the line of the main cableway. This causes the loading cableway to extend in the same general direction, and preferably slightly to one side, of the main cableway, as is indicated in Fig. 2. 75

As the logs are brought in by the main cableway, they are dropped anywhere within the range of action of the loading cableway 3. This may possibly be at some distance from the head mast. The two cableways extending substantially in the same direction from the head mast, the supplemental, or loading cableway, may pick up the log and bring it along to the loading position. As, however, the cableway is shifted 80 in its angular direction from the head mast it will, throughout at least one-half of its positions, extend away from the track. The position of the track relative to the head mast is shown in Fig. 2. The track 80 is the 85 main line upon which the cars being loaded stand. The car upon which the engine and the operating mechanism for the cableway rest is shown at 9. In some cases the operating engine will be mounted upon a skid instead of upon a car. In either case it will 90 be located close to the base of the head tree. 95

In the position of the main cableway 2 and the loading cableway 3, as shown in Fig. 2, it would not be possible to load cars standing upon the main line track 80, using these cableways alone. This condition would exist in all positions of the cableway excepting those in which it extends across and over the loading track. It is for the purpose of obviating this difficulty and to make it possible 100 to load a car upon the same track for all positions of the cableway, that this invention is provided.

The supplemental or loading cableway 3, 110 has a carriage 30 mounted to travel thereon, and this is operated by two lines, 4 and 41,

the line 4 extending to and through a sheave 40, supported from the cable 3, and thence back to a connection to the carriage 30, while the line 41 extends from the carriage 5 over a suitable support or sheave carried by the head tree and thence to the drum by which it is handled. A pick-up line 42 extends from the engine over a sheave 45 carried by the head tree and thence over a 10 sheave 44 carried by the carriage 30, and thence either to a direct connection to the load, or about a suitable sheave, or sheaves, 43, by which the load-lifting capacity is increased. The log 70 is shown as picked up 15 and supported by a log-loading rig 7, which employs a spreader. This rig would be engaged by the fall block 43. By this means any log lying at any point beneath the supplemental cableway 3 may be picked up and 20 brought in to the head tree.

Extending from the head tree 1, in such a direction as to extend across the loading track, is a guy-line 5. Secured upon or from this guy-line, is a line sheave 50, through 25 which passes a transfer line 6. This line extends from the engine, over a sheave 53, carried by the head tree, thence over the sheave 50, which is carried by the line 5, at an elevated position and at a position beyond 30 the loading track. This transfer line is then led, in any suitable or desired manner, back to the mechanism by which the log is picked up by the line 42. As herein shown, this line first extends over a sheave 52, carried 35 by the guy-line 5, out farther toward its outer end, thence over sheave 51 carried nearer to its inner end and thence to the load-lifting device.

When a log has been brought by the loading line in to a position adjacent to the head tree and is thus suspended in elevated position, the transfer line 6 is hauled in by its 40 drum and the pick-up line 42 is, at the same time, allowed to pay out. In consequence, 45 the log is transferred laterally of the supplemental or loading cableway 3, until it is brought into position over the car. The transfer line then acts as a carrying or supporting line for the log. If it is paid out 50 and at the same time the pick-up line is correspondingly paid out, the log will be lowered upon the car. The position of the 55 log at this time will be determined by the manner of handling these two lines. It is thus possible to drop the log at any point 60 between the position of the carriage 30 and the position of the sheave 50. By locating this sheave a sufficient distance from the head tree 1, the log may be loaded upon one

The guy-line 5, upon which the transfer line is mounted, need not be shifted in position, except possibly once during the handling of the entire tract of timber. A single position of the transfer line is capable 65 of handling the logs brought in by the cableway while shifting through a large sector. By the use of this device, loading of the logs is greatly facilitated. It is not necessary to shift the track to correspond to the shifting of the main cableway.

What I claim as my invention is:

1. A log handling apparatus comprising a head mast, a main or hauling cableway extending from said mast and provided with means for bringing in logs, a loading cableway extending from the same mast in substantially the same direction as the main cableway and provided with means for bringing in logs, a guy line extending from the same mast in a direction diverging from that of the cableways, a guide sheave carried in elevated position by said guy line and a transfer line extending through said sheave and connecting with a load-supporting member of the loading cableway.

2. A log handling apparatus comprising a head mast, a main or hauling cableway extending from said mast and provided with means for bringing in logs, said means including a haul-back line and a distant guide sheave for the haul-back line carried by the trackway cable, a loading cableway extending from the same mast in substantially the same direction as the main cableway and provided with means for bringing in logs, a guy line extending from the same mast in a direction diverging from that of the cableways, a guide sheave carried in elevated position by said guy line and a transfer line extending through said sheave and connecting with a load-supporting member of the loading cableway.

3. A log handling apparatus comprising a head mast, a main or hauling cableway extending from said mast and provided with means for bringing in logs, a loading cableway extending from the same mast in substantially the same direction as the main cableway, said loading cableway carrying a guide sheave for the haul-back line near its outer end, a guy line extending from the mast in a direction diverging from that of the cableways, a guide sheave supported in elevated position from said guy wire, and a transfer line passing through the latter sheave and extending to the load carried by the loading cableway mechanism.

AUGUST DANIELSON.
